UNITED STATES PATENT OFFICE.

JOHN S. WINTON, OF MILFORD, IOWA.

CORN-RACK.

942,694.

Specification of Letters Patent. Patented Dec. 7, 1909.

Application filed October 30, 1908. Serial No. 460,253.

To all whom it may concern:

Be it known that I, JOHN S. WINTON, a citizen of the United States, and a resident of Milford, in the county of Dickinson and State of Iowa, have invented a new and Improved Corn-Rack, of which the following is a full, clear, and exact description.

This invention is an improved rack and belongs to that class of such devices in which a number of corn-ear impaling-pins project from a support and sustain the ears in spaced relation and at known points during the period of curing, storing and testing.

The invention consists of a supporting member and corn-ear impaling pins inclining upwardly and outwardly from the opposite faces of the member, with one of said pins passing through the member and integral with the pin at the opposite side.

Reference is to be had to the accompanying drawings forming a part of this specification, in which similar characters of reference indicate corresponding parts in all the views.

Figure 1 is a perspective view of a seed corn rack constructed in accordance with my invention, the same showing a number of ears of corn engaged on the impaling pins; Fig. 2 is a fragmentary vertical section of the rack on an enlarged scale; and Fig. 3 is a fragmentary perspective view of a modified form of the rack.

In producing a rack in accordance with my invention I make use of base blocks 5, each having a roller 6 supporting each end, and carrying a standard 7. The standards 7 rest or seat on the base blocks and are reinforced therewith by struts 8 which are arranged at both sides. The standards 7 are rigidly connected together by a board 9 arranged therebetween, and also by a top rail 10, the rigidity and strength of the structure being further augmented by braces 9^a, respectively attached to the ends of the base blocks and to the board near the ottom edge thereof. The board 9 is provided with a series of corn-ear impaling pins 11, each pro-

jecting outwardly and inclining upwardly from both faces of the board. The pins are preferably constructed of a piece of wire 50 having a substantially right-angular bend at one side of its center, each wire affording two pins projecting from opposite sides of the board, as shown in Fig. 3. The longer pin of the wire is driven or otherwise passed 55 through the board at an angle such that both pins will project substantially equal distances from the opposite faces of the board. The pins are arranged in horizontal and vertical rows, each row being provided 60 with a number or other designation, whereby the ear of corn on any pin may be readily located. The construction of the rack admits of its being easily shifted to a removed position when not in use or after several 65 seed have been selected from each ear for the testing operation, enabling a relatively large number of the racks to be conveniently kept in small quarters.

In Fig. 3 I have shown a modification of 70 the board 9, which, instead of being constructed of a flat single piece, is made of a number of separate slats, each of which is provided with a row of pins arranged in the direction of its length. The word "board" 75 in the specification is used in its broader sense and may be of wood or other material of composite construction.

Having thus described my invention, I claim as new and desire to secure by Letters 80 Patent:

The combination of a supporting member, and corn ear impaling pins inclining upwardly and outwardly from the opposite faces of said member, with one of said pins 85 passing through the member and integral with the pin at the opposite side.

In testimony whereof I have signed my name to this specification in the presence of two subscribing witnesses.

JOHN S. WINTON.
